UNITED STATES PATENT OFFICE.

JOSEPH L. COX, OF BATTLE CREEK, MICHIGAN, ASSIGNOR TO THE DUPLEX PRINTING PRESS COMPANY, OF SAME PLACE.

APPARATUS FOR SEVERING SHEETS FROM WEBS OF PAPER.

SPECIFICATION forming part of Letters Patent No. 478,409, dated July 5, 1892.

Application filed November 1, 1889. Serial No. 328,949. (No model.)

To all whom it may concern:

Be it known that I, JOSEPH L. COX, of Battle Creek, in the county of Calhoun and State of Michigan, have invented certain new and useful Improvements in Apparatus for Severing Sheets from a Web of Paper, &c.; and I do hereby declare that the following is a full, clear, and exact description thereof, reference being had to the accompanying drawings, and to the letters of reference marked thereon, which form part of this specification, in which—

Figure 1 is a side elevation, partly in section, of my improved machine for dividing a web of paper into separate sheets. Fig. 2 is a detail view of the paper-breaking device. Fig. 3 is a detail end view of the perforating-blades. Fig. 4 is an edge view thereof. Fig. 5 is a side view of the cylinder and paper breaking and carrying devices. Fig. 6 is a sectional view showing the adjusting devices for the journals of the perforating-blades and the paper-feed rolls.

This invention is an improved machine for severing sheets of paper from a continuous web or roll thereof; and its object is to provide improved mechanism which can be adjusted to cut sheets of paper of any desired length from the web, and incidental to this object to provide means for perforating the paper after its passage through the feed-rolls, to provide devices for breaking the sheets from the web on the line of perforation thereof and removing them from the carrier-tapes, and to adjustably mount the perforating mechanism in relation to the breaking devices, that when the length of the sheet has been altered the parts can be readily shifted, so as to bring the edges of the new-length sheets up to the proper point for action of the breaker, all of which objects are attained by the mechanism illustrated in the drawings, which consists, essentially, in novel devices for regulating the speed of the paper-feed rolls, novel adjustable perforating-blades mounted on removable shafts whose speed can be varied according to the speed of the paper-rolls, and in a series of carrier-tapes, and a gripping-cylinder whereby the perforated sheets of the web are broken off, and in certain other

novel details of construction and arrangement of parts hereinafter described and claimed.

Referring to the drawings by letter, A designates a frame mounted on a base A' and rendered longitudinally adjustable on said base by means of a screw A², operated by bevel-gears and a shaft, as indicated in the drawings, frame A moving on guides A³, formed on the base, as indicated, so that it will be kept from lateral displacement thereon.

At the rear end of frame A are journaled in proper bearings thereon three paper-feed rolls B B' B², one above the other, and of equal diameter. At the opposite end of frame A are two shafts C C', one vertically above and parallel with the other, the said shafts being journaled in vertically-adjustable boxes C² C², which move in suitable openings in the sides of frame A and which are transfixed by a vertical screw-rod C⁴, which has right and left hand threads on its upper and lower ends, that respectively engage correspondingly-threaded openings in the upper and lower boxes C², as indicated, so that by turning rods C⁴ the boxes are brought toward each other or separated, as is obvious, thus altering the relative positions of shafts C C'. Rod C⁴ can be operated by true-gears C⁵, as indicated.

D designates a bar having a series of hangers, being slotted and projecting from one edge at right angles to the bar, which hangers are secured against a plain surface of shaft C by means of screw-bolts or hand-nuts D² D², as shown, by which bar D is rigidly connected to said shaft between the journal-boxes thereof and is revolved therewith, and by means of these slotted hangers the bar D can be adjusted closer to or farther from shaft C and parallel therewith and locked in such position. In the lower edge of bar D is a longitudinal groove, in which is placed a packing-strip D³ of yielding material—such as rubber or wood—to receive the impact of the perforating-blade.

d is a bar similar to bar D and having a series of hangers d', by which it is mounted on shaft C' by screws or bolts d² d², as shown in Fig. 3.

d³ is a perforating-blade secured to the face of bar d by bolts or nuts, as indicated, and 100

whose edge is preferably serrated and projects beyond the edge of bar d , and the bars D d are so adjusted on shafts C C' that as the latter revolve the bar-blade d^3 impinges against and indents the packing D^3 once for each revolution of the said shafts.

c c' are intermeshing gears on the ends of shafts C C' , which gears are removable and may be replaced by others of different diameter, which can be made to properly intermesh by adjusting the shafts vertically by the means described, and when the positions of the shafts are altered bars D d have to be correspondingly shifted thereon to permit the proper action of the perforator-blade.

b b' b^2 are similar intermeshing gears on the shafts of the paper-rolls.

E is a gear on the shaft of the lower roll B^2 , intermeshing with a gear E' , journaled on a stub-shaft carried by an adjustable bracket E^2 , the upper end of which is pivoted on a fixed stud on the main frame or on the shaft of roll B^2 , if desired, while its lower end is slotted, and through this slot passes a bolt E^3 , by which the bracket can be locked in any position to which it is swung. Gear E' also meshes with the gear c' on shaft C' , consequently transmitting motion from the paper-feed-roll shaft to the perforating mechanism. Gear E' is thus adjustably mounted, so that when gears of different diameter are placed on shaft C' it can be moved toward or from said shaft, so as to intermesh with the new-size gear and transmit motion thereto.

F designates a shaft journaled transversely of the frame A at top thereof, and F' is a gear on the end of said shaft, which can be removed and replaced by other gears of different diameters, as desired.

f designates a pinion mounted on the end of a pivoted lever f' , which is journaled on a stud fixed to the main frame or may be on the shaft of the upper roll B at the side of the frame adjoining gear F' . Pinion f can be shifted by this means to intermesh with gear F' and with gear b on the shaft of roll B , as shown, and can be readily shifted to mesh with gears F' of different diameters. The other end of lever f' carries a bolt and hand-nut which engages a slot f^2 in a segment f^3 , secured to the frame A , by which the lever can be locked in any position desired.

G designates one cylinder of a rotary printing-press of any suitable construction and which stands opposite the end of frame A , and g designates the gripper-fingers of the cylinder, operated by ordinary mechanism to grip a sheet of paper delivered to the cylinder by upper and lower tapes H H' . Tapes H run over rollers H^1 and tapes H' over rollers i and over pulleys j on a shaft J , journaled in bearings (not shown) below cylinder G and operated by a gear K , driven by a gear k on the cylinder, as indicated in the drawings. The rollers I i , as shown, are journaled in brackets L , rising from base A' opposite cylinder G .

M designates a bevel-gear on the end of the shaft of cylinder G , intermeshing with a bevel-gear M' , loosely splined on a shaft M^2 and driving the latter. This shaft M^2 extends forward to shaft F , and on this end of the shaft M^2 is keyed a bevel-gear m on shaft F . The end of shaft M^2 plays longitudinally through the gear M' when frame A is adjusted toward or from cylinder G . The cylinder is driven from the main shaft of the press by suitable connections, (not shown,) and transmits motion to the paper-feed rolls and perforating devices through the shaft M^2 , as is obvious. On the shaft J , at points intermediate the pulleys j , are keyed disks N , which have one peripheral tooth or stud n , as shown, these several teeth being in line and arranged to contact with the periphery of cylinder G between the gripper-fingers thereof, as indicated in Fig. 5, and clamp the edge of the sheet momentarily against the cylinder while the grippers are closing thereon, for a purpose hereinafter shown.

In operating the device the web of paper W from a roll X is fed over roll B down between the same and roll B' and B^2 and forward between shafts C C' to the tapes H H' , by which the end of the web is continually combed or coaxed forward toward the cylinder, which is so speeded that its periphery and the tapes H H' have a speed or travel much faster than the paper web fed into the machine—about twice as fast as the paper web is fed when the longest sheets are being severed therefrom.

If it is desired to cut sheets of about thirty inches length, which for the sake of explanation may be assumed as the length of sheet W for which the press, as shown, is adjusted, the periphery of the travel-cylinder G and the tapes travel faster than the web, and for each revolution of the cylinder the paper-rolls feed out thirty inches of the web. The shafts C C' are so geared up to the roll-shafts, as described, that they make one revolution for each revolution of the cylinder and for each thirty inches of web fed out by the paper-rolls, so that at regular intervals the web is perforated. Shafts C C' are so speeded that the perforating-blades travel in their revolution by said shafts at the same speed as the paper passing between them—that is, the circle described by the edge of the perforating-blade is thirty inches in circumference and passed through by the blade at the same speed that the paper travels, this being easily effected by interchangeable gears on shafts C C' , as described. The web after being perforated is received by tapes H H' and drawn toward the cylinder G , which is adjusted so that at the moment the edge of the web is brought by the tapes into position for engagement by the gripper-fingers g the latter will be ready to clamp and do clamp the edge of the web, and simultaneously the teeth n on disks N bind the edge of sheet against the periphery of the cylinder. Now it should be remembered that the

cylinder and tapes are traveling faster than the web, and hence the moment teeth *n* bite the paper against the periphery of the cylinder, aided by the action of the gripper-fingers, 5 a sudden jerk is given to the web and fracture thereof is caused along the line of perforation separating the sheet from the web, as indicated in the drawings. As the cylinder and disks *N* revolve, the studs *n* release the 10 paper and the gripper-fingers carry the severed sheet around the periphery of cylinder *G* to a point where it is stripped off by mechanism. (Not shown.) By the time the cylinder has completed a revolution and the paper-rolls 15 have fed out the perforating mechanism has perforated another length of paper on the web, the edge of which the tapes *H H'* have brought into position to be engaged by the cylinder-grippers and severed, as before de- 20 scribed, this operation being continuous, the mechanisms being so timed and speeded that a length of web corresponding to the size of sheet desired is perforated at the proper point and fed up into position for engagement 25 by the cylinder-grippers during each revolution of the cylinder. It will be observed that the point of severance of the web or breakage thereof is always about thirty inches from the point where the gripper-fingers engage 30 its end edge, and if the feed is properly adjusted so as to pay out and perforate thirty additional inches of web at each revolution of the cylinder the advancing edge of the web will be always brought up to the proper 35 point for engagement by the gripper-fingers at the moment the cylinder completes one revolution.

When it is desired to cut different lengths of paper, it is only necessary to adjust the 40 speed of the paper-feed rolls that only the desired length of web will be paid out and perforated at each revolution of the cylinder. This of course will naturally throw the point of separation of the web closer to the cylinder for shorter sheets or farther therefrom for longer sheets, and it is necessary to bring the edge of the new-length sheets to the point of engagement with the gripper-cylinders at each revolution thereof. It is first necessary 45 to change the speed of the paper-feed rolls and perforating-blade so that but the requisite amount of paper web will be fed out and perforated, and to change the belt the gear on shaft *F* is removed and another gear substituted which will impart the desired length 50 of paper.

To change the perforating mechanism, gears *c c'* are removed from shafts *C' C* and others substituted therefor, which will cause one 55 revolution of said shafts during the paying out of the requisite length of paper web. By means of the adjustable gears the new gearing is readily intermeshed. This provides for the regular feeding of the web, and the only 60 other adjustment is to bring the edge of the new sheets into position for engagement by the grippers which, as the parts stand, may

fall short of or project beyond the grippers. This is readily remedied, however, by stopping the cylinder and paper-feed rolls and 70 throwing gear *E* out of engagement with gears *c'*, thus disengaging the perforating mechanism from the paper-feed rolls, and the operator then turns shafts *C C'* by hand and moves the perforating-blade back and forth. If the 75 edge of the web fell short, he would move the blade back just so many inches as the edge fell short. If the edge projected beyond the grippers, he could move the blade forward just so many inches. Then by throwing gear *E* back into engagement and starting the press 80 the web would be perforated in such manner that the edge will properly come beneath the cylinder. Of course the end of the web lying between the perforating-blades and cylinder 85 will have to be pulled out and thrown aside, as it will not be properly perforated, but the succeeding and following sheets will be. The perforating-blade must be adjusted also for each adjustment of the paper-feed rollers, so 90 as to travel at the same speed as the paper. This is necessary, else if the perforating-blade moves faster or slower than the web it will 95 jag the web while perforating it, while if it moves at the same speed it will perforate evenly and cleanly. If it was found that the edge of the sheet fell short of or went beyond the cylinder-grippers, instead of having to throw the cylinder out of gear or stop its motion, the portion of the web in the frame *A* could 100 be bodily advanced or retracted by shifting frame *A* toward or from the cylinder, the web paying off the roll and not altering its position on the feed-rollers or between the perforating devices, but its edge moving up to- 105 ward or back from the cylinder, as is obvious. Thus after the gearing has been altered to feed different lengths of paper the frame *A* can be shifted to bring the edge of the web into correct position for engagement 110 by the gripping-fingers. By having a number of interchangeable gears of varying sizes for changing the speed of the feed-rollers and perforating-blades, as described, the machine can be very readily adjusted to sever the 115 web into various lengths, as desired. It will be observed that the tapes do not effect the severing of the sheets from the web, but merely direct it to the cylinder, the severing being effected by the simultaneous action of 120 the gripping-fingers and the teeth *n*, as described, which positively bite the edge of the web simultaneously, and thus obviate any possibility of unequal strain on the web in breaking off the sheets, which is a common 125 defect in machines wherein the sheets are broken by the combing action or differential speed of the delivery-tapes, which require an extreme nicety of adjustment hard to attain and yet harder to retain. 130

Having thus described my invention, what I claim is—

1. The combination of the shafts *C C'*, the bars *D d*, adjustably secured to said shafts

by slotted hangers and bolts, substantially as described, the impact-strip in bar D, the perforating-blade secured to bar d, and the interchangeable gears on said shafts, with the 5 paper-feed rolls, the gears thereon, and the movable gear mounted in an adjustable bracket and adapted to transmit motion from the roll-shafts to the shafts C C', substantially as described.

10 2. The combination of the paper-rolls inter-geared, as described, the horizontal shafts F, driven by gearing from a press-cylinder shaft, the interchangeable gear on shaft F, and the gear mounted on an adjustable bracket for 15 transmitting motion from the gear on shaft

F to the roll-shafts, with the shafts C C', the cutter-blade and impact-bars adjustably mounted on said shafts, and the interchangeable gears thereon, and the gear mounted in an adjustable bracket for transmitting motion from the roll-shafts to the shafts C C', substantially as described. ²⁰

In testimony that I claim the foregoing as my own I affix my signature in presence of two witnesses.

JOSEPH L. COX.
